HUGH S. KERR, OF PHILADELPHIA, PENNSYLVANIA, ASSIGNOR TO ISRAEL FOSTER, OF SAME PLACE.

Design No. 4,632, dated February 7, 1871.

DESIGN FOR A CARPET-PATTERN.

The Schedule referred to in these Letters Patent and making part of the same.

I, HUGH S. KERR, of Philadelphia, county of Philadelphia, State of Pennsylvania, have invented produced a Design for a Carpet-Pattern, of which following is a specification.

The figure in the accompanying drawings represent a specimen of a carpet-pattern to illustrate my design, the main characteristics of which are Figures A, (one-fourth only of each figure being shown,) ornamental medallions B, and the space bounded by the medallions and figures A, which space is ornamented by bunches, leaves, and flowers, too clearly shown in the drawing to need explanation.

Respective of the colors employed—claim—

1. The design for the ornamental figures A, as described and shown;
2. The design for the ornamental medallions B, as illustrated;
3. The design for the foliated space, bounded by the said figures and medallions; and
4. The design for the entire pattern, including figures A, medallion B, and said foliated space.

In testimony whereof I have signed my name to this specification in the presence of two subscribing witnesses.
